UNITED STATES PATENT OFFICE

155,836

DESIGN FOR A COMBINED ASH TRAY,
CIGARETTE AND MATCH HOLDER

Joe Pfleger, Chicago, Ill.

Application March 21, 1949, Serial No. 1,513

Term of patent 14 years

(Cl. D85—2)

To all whom it may concern:

Be it known that I, Joe Pfleger, a citizen of the United States, residing at Chicago, in the county of Cook and State of Illinois, have invented a new, original, and ornamental Design for a Combined Ash Tray, Cigarette and Match Holder, of which the following is a specification, reference being had to the accompanying drawings, forming part thereof.

Fig. 1 is a front perspective view of a combined ash tray, cigarette and match holder, showing my new design;

Fig. 2 is a left hand end elevational view of Fig. 1;

Fig. 3 is a right hand end elevational view of Fig. 1;

Fig. 4 is an exploded front elevational view thereof; and

Fig. 5 is a top plan view of the bottom portion of Fig. 4.

I claim:

The ornamental design for a combined ash tray, cigarette and match holder, as shown.

JOE PFLEGER.
